STRUCTURAL MEMBER AND BUILDING
STRUCTURE

Erwin A. Horn, Irving F. Laucks, and P. Bobbin
Attwell, Seattle, Wash., assignors, by mesne assignments, to I. F. Laucks, Inc., Seattle, Wash., a corporation of Washington

Application July 24, 1939, Serial No. 286,266

5 Claims. (CL 20—91)

The present invention relates to new structural members which are in the form of curved members having curvature in a single plane and are made up by a laminated construction out of adhesively united wood plies, the members being adapted for use as beams, arches, and the like. The invention also relates to building structures with frames composed of the new members.

While the structural members of the present invention are of general utility, we have found them to be especially advantageous in the construction of arched frame work for buildings, two of the members, preferably, being utilized in the formation of each arch. We have found most effective from every point of view, a frame work consisting essentially of two arches arranged in vertical planes as the diagonals of a rectangle and secured to other arches arranged as the sides of the rectangle, said other arches defining openings to wings leading from the main enclosure which is framed by the crossed arches. In this construction, a flooring may be provided across the lower ends of the arches, and the latter connected by tie rods located below the flooring. The arches may be directly sheathed, as by plywood panels, to provide a roof and side walls.

For uses such as herein contemplated, wood has the important advantages of a high ratio of strength to weight, relatively low cost, and ease of fabrication. However, for curved framing members which are required to carry heavy loads, the forests do not provide material having the necessary dimensions and properties, or at least, material of the right character is not readily available.

In making curved beams of this character, such as are often required for roof supports and similar uses, it has been heretofore necessary to use a laminated construction and to bend the individual laminae to the proper curvature and then hold them together in the bent position with heavy clamps while the glue was setting. This involves undesirable initial stresses on the parts and also necessitates shop construction and a costly equipment of heavy and often special clamps or forms to permit making up particular shapes. In the case of large buildings, requiring long and heavy beams, this prefabricated construction involves the troublesome feature of transporting a long heavy shape from the shop to the job. There is also the difficulty that such beams have a tendency to spring out of shape and distort when the clamping pressure is released or when moisture changes take place, since the wood laminae remains under stress due to the

initial bending. We have now discovered that these difficulties can be avoided and a widely useful and stronger curved laminated beam can be built up at less cost by adopting a different arrangement of laminae and method of fabrication.

In our method of fabrication we may eliminate bending of the laminae entirely so that in our beam the edges of the laminae rather than their flat surfaces are opposed to the direction of the principal stress. This does not have to be done in the shop but can be done, if desired, on the job and thus save the cost of transporting heavy and cumbersome shapes. We cut out the individual laminae in the flat, usually with a band saw, and then assemble them with interposed adhesive in flat position using butt or in some cases scarf joints at the end junctions of individual pieces where a plurality of pieces are present in a single laminae. The joints of adjacent laminae are staggered in such manner that these joints cause a minimum of local weakness. The parts are then assembled on any flat supporting surface with interposed glue which is preferably of a self-bonding or quick setting character requiring a minimum of pressure. For this purpose many casein glues are very suitable. After the laminae have been assembled with glue of this character, they can in most cases be merely nailed together to hold them in proper relation while the glue is setting. It is, of course, seen that this method is restricted to the fabrication of beams having curvature in only a single plane, but this restriction is of no practical importance because it is practically never necessary to use beams having curvature in more than one plane.

The material selected for the laminae is generally wood, although other available materials which can be adhesively united such as artificial lumber, paper, plastics, etc., may also be used without departing from the principles of the invention. Therefore, when the term wood is used in this specification and the appended claims, it is to be considered as used in a generic sense and to embrace both natural wood and also such equivalents. When using wood, the elements may consist either of sawn lumber, thick or thin boards, single ply veneer, or plywood, particularly the ordinary plywood of three-ply construction. We find that plywood is an especially useful material. In general, it can be used as if it were a single ply of the same total thickness, notwithstanding the presence of the middle cross ply.

The laminae for straight portions in the beam are sawed out from sheet material according to the layouts required while the curved portions are band sawed to the shape of the section of the beam which they are to occupy. In band sawing the parts are cut so as to maintain the grain of the laminae in the general longitudinal direction of the beam. There is very little waste because most of the pieces which are left over after cutting up a sheet or a board can be matched together with similar pieces to form laminae or portions of laminae.

While it is, of course, desirable to have the individual plies as long as is permitted by the available material, nevertheless, unless the plies are comparatively thick, butt joints do not cause any serious local weakness provided the locations of the joints in the respective laminations are well staggered so as not to have too many butt joints come close to any given point in the beam. In some instances where the beams are being built up out of laminations of sawn lumber and a comparatively small number of laminations is used to make up the thickness of the beam, it may be desirable to scarf and glue the ends of the pieces instead of using butt joints. Where the raw material is thin and the laminations numerous, this precaution is unnecessary.

In some instances, however, while we make the principal section or core of our beams with laminae on edge, we may supply an additional outer reinforcing layer, stress covering, or tire consisting of additional laminae bent and adhesively united to a core or main construction made up with laminae placed on edge. The advantages of our simple method of building the core are thus retained and there is the further important gain that the core can then act as its own form for gluing on the edge covering or coverings at locations calling for increased section. This solves the problem of adding stress coverings to curved beams on the job because this can now be readily done by providing a smooth surface on the edge of the beam requiring reinforcement, and then nailing or clamping on the covering with interposed adhesive. Reinforcing covering along any curved portions of the beam are added as required and the surfaces held in contact by means of either nails or hand clamps until the glue has set. Thus no special forms are needed even when curved members are being fabricated. In both instances, that is, in the case of beams wholly made of laminae on edge or in cases requiring added tires as stress coverings, we thus eliminate the necessity both for shop construction and the use of elaborate glue clamps.

The use of stress coverings or tires in conjunction with our "on edge" core construction is particularly advantageous in building thick beams because special material to form an outer skin to resist tension is then easily applied where required on a core of coarser or cheaper material, because by our method the core serves as a ready-made form.

As regards strength, we have found that if two beams are made up to the same section out of a multiplicity of parallel glued laminations and one is tested as a beam with the bending force applied perpendicularly to the surface of the plies and the other with the beam on edge, the "on edge" construction is considerably stronger. This is true either with straight or curved beams, and in the latter case, is due in

part to eliminating the bad effects of the initial stresses when curved beams are made by bending and gluing the laminations in forms. Thus, our construction, besides eliminating the necessity for shop manufacture and for shop bending, has the further advantage of gaining additional strength with the same section.

In one instance, tests were made with a number of identical small, straight, square beams, all glued up out of $\frac{1}{8}$ " Douglas fir veneer laminations. When tested with the load applied on the flat side, the ultimate strength averaged 6150 pounds, but the average of duplicate tests with the load applied on edge was 8080 pounds. The deflection under load was also much less at all loads when the beam was placed on edge. This same difference in favor of "on edge" construction was found to obtain with curved beams. Thus our on edge construction is seen to provide added strength in addition to the other advantages.

In many instances owing to its general availability in large sheets, three ply Douglas fir plywood is a particularly suitable material for the construction of these curved beams. It would naturally be thought that in this instance the presence of the middle ply having the grain running in the short direction across the beam would reduce the strength at least one third. In practice, provided the cross grained ply is not more than one-third of the total thickness, this does not appear to be the case. In fact, we find that a curved beam made up out of a series of layers of plywood having the outer ply of each piece running lengthwise, when stressed on edge, is almost as strong as a beam of the same size made with all the plies running lengthwise and also placed on edge. It seems probable that in this instance the middle ply of the plywood serves to a considerable extent as a tie to hold the tension bearing lengthwise fibers of the outer plies in proper position to more effectively resist the load.

The advantage of using plywood in constructing beams of this sort is often important because of its cheapness, large size, ready availability, and the ease with which it can be band sawed to the proper contour for use in constructing curved sections.

Reference will now be made to the accompanying drawings which illustrate structural members and frame work as contemplated under the invention.

In the drawings:

Figure 1 is a plan view of arched framing for a building structure, the framing providing for a main central edifice and four wings leading therefrom.

Figure 2 is a perspective of the framing of Figure 1, two only of the wings being shown.

Figure 3 is a section substantially on line 3-3 of Figure 1.

Figure 4 shows in perspective a curved structure element appearing in the preceding figures, and

Figure 5 shows in perspective an end portion of a structural element involving a laminated core and laminated edge coverings.

Referring to Figures 1 to 4, reference numerals 10 and 11 indicate generally a pair of arches arranged as the diagonals of a square and composed, respectively, of identical half arch portions 12, 13 and 14, 15, portion 15 being shown alone in Figure 4.

This curved member or beam 15 has an upright

portion 16 and a portion 17 upwardly inclined away from portion 16, the two portions being joined by a curved section 18. The member 15 is made up of a suitable number of laminae and ordinarily, and especially in the case of a member of any considerable size, each individual laminae is composed of a number of pieces. For example, the face lamina visible in Figure 4 includes the pieces 19, 20, 21, 22, 23, 24 and 25 in longitudinally extending relation and the contiguous ends may have suitable butt joints as at 26, or scarf joints as at 27 and 28. The laminae may be composed of any of the materials heretofore mentioned, which material in Figure 4 may be contemplated as being plywood, this material ordinarily consisting of three plies with two outer plies having the grain running in the same direction, while the grain of the inner ply runs transversely. The pieces are cut so that the grain, or predominate grain, runs generally lengthwise of the structural member. In carrying out this principle, the illustrated pieces 22 and 23 at the curve have the grain running substantially tangential to the curve.

Pieces 22 and 23 have a lateral joint 29, and this is lapped by the underlying lamina which at the curve may be cut from a single piece to the full width of the beam. Similarly, the end joints of the pieces of the underlying lamina are staggered, as at 30, so as to be lapped. In all cases, the joints whether lateral or end joints, are lapped so that no joints of adjacent laminae are in registry. These joints are all ordinarily glued.

In the case of the beam 15, its upper end is brought to a 90° point 31, which mates with similar points of the other beams, as shown in Figure 1, so that the arches, which as here shown are at right angles to each other, intersect at their apices where they are securely united in any suitable manner.

In setting up the framework constituted by arches 10 and 11, the lower ends are set on suitable footings and the lower ends of the arches are connected by tie rods 32 and 33, Figures 1 and 3.

Arches 34, 35, 36 and 37, preferably formed of identical half arch portions made up as previously described, are arranged as the sides of the square and their upright portions are bolted through the upright portions of the main arches, as indicated, for example, at 38 and 39, Figure 2. The half portions of arches 34 to 37 are securely connected together in any suitable manner at their upper ends, and their lower ends are connected by tie rods as at 40 and 41, Figure 2, so that a very rigid framework is provided.

Arches 34 to 37 may be utilized as defining openings to wings whose framework is completed by similar arches 42, 43 in faced parallel relation with respect to arch 34, arches 44 and 45 similarly disposed with respect to arch 35, arches 46, 47 with respect to arch 36, and arches 48, 49 with respect to arch 37. The lower ends of each of the arches are preferably connected by a tie rod.

As here shown, the apices of all of the arches are of the same height so as to provide four horizontal ridge lines. These lines may be carried out by rafter assemblies 50, 51, 52 and 53, secured in rectangular relation between the crossed arches 10 and 11, and providing a slope the same as the top slope of the wing arches, which slope is also carried out by the upper portions of the crossed arches. That is to say, the top edges of

arches 34, 42 and 43, of rafter assembly 53, and of arch portions 12 and 15, for example, lie in the same two angularly related planes.

According to the most economical practice, the arches are not connected by any permanent horizontal framing, but are merely temporarily braced, while sheathing, which may be in the form of plywood panels, is applied and secured in place.

10 As shown in Figure 3, sills, as at 54, may be provided, these supporting joists 55 on which is laid a floor 56 above the tie rods.

A structure as above described may be very economically produced and provides a maximum amount of free interior space and has great strength. As one example, we have erected in a northern climate, where heavy snow falls are encountered, a building in accordance with the present invention with crossed main arches, each with a span of sixty-one feet, and wing arches with a span of forty-three feet. In this case, the main enclosure defined by the cross arches was designed as an auditorium, tiers of benches being arranged in the wings.

25 The built up beams may be made of any desired size and strength and for additional strength one or both of the edges of the on-edge laminae may be provided with an adhesively applied bent stressed covering of one or more laminae. In Figure 5, a core portion is shown as made up of a multiplicity of laminae 57, which have staggered lateral and end joints and which are arranged parallel to the plane of the curve. Two laminae 58 and 59 are applied to the inside of the beam and four laminae 60, 61, 62 and 63 are applied to the outside of the beam. Superposed laminae have staggered lateral joints as at 64 and 65, and staggered end joints, as at 66 and 67.

40 From the above, it will be seen that the make-up of the curved structural members can be considerably varied, as can also their curvature, in order to take care of the situation in hand. Changes may also be made in the arrangement and relation of the arches in a building structure. Accordingly, we do not limit ourselves with respect to these matters except as in the following claims.

We claim:

50 1. A laminated structural member having curvature in a single plane and consisting of adhesively united flat plywood laminae which are substantially parallel with the plane of curvature of the member, the laminae being each composed of a plurality of contiguous pieces in longitudinally extending relation; the pieces each comprising outer plies with the grain running in the same direction and an inner ply with the grain running transversely with respect to the grain of the outer plies and the pieces being disposed with the grain of the outer plies running generally longitudinally of the member.

55 2. A laminated adhesively bonded structural member having curvature in a single plane, said member including laminae composed of a plurality of contiguous pieces in longitudinally extending relation substantially parallel with the plane of curvature of the member, said pieces each comprising outer plies with the grain running in the same direction and an inner ply with the grain running transversely with respect to the grain of the outer plies and the pieces being disposed with the grain of the outer plies running generally longitudinally of the member.

60 3. A structural member as set forth in claim 2.

with the added feature that a bent stressed covering of wood is adhesively applied to at least one edge of the member.

4. A laminated adhesively bonded structural member having a zone of relatively sharp curvature in a single plane, the laminae of said member in said zone of curvature being composed of plywood pieces substantially parallel with the plane of curvature of the member, said pieces each comprising outer plies with the grain running in the same direction and an inner ply with the grain running transversely with respect to the grain of the outer plies, and the pieces being disposed with the grain of the outer plies running generally lengthwise of said zone.

5. A laminated adhesively bonded structural member comprising generally straight end por-

tions and a relatively sharply curved portion joining said end portions, the laminae throughout being substantially parallel with the plane of curvature of said curved portion and each lamina being composed of pieces disposed end to end with the joints between the pieces of each lamina lapped by the pieces of the adjacent lamina, the pieces which form said laminae being of plywood comprising outer plies with the grain running generally lengthwise of said member and an inner ply with the grain running transversely with respect to the grain of the outer plies.
